UNITED STATES PATENT OFFICE.

OTTO KAMPFE, OF NEW YORK, N. Y.

SHOW-CASE.

No. 830,076.

Specification of Letters Patent.

Patented Sept. 4, 1906.

Application filed October 28, 1904. Serial No. 230,300.

To all whom it may concern:

Be it known that I, OTTO KAMPFE, a citizen of the United States, and a resident of the borough of Brooklyn, county of Kings, city and State of New York, have invented a new 5 and useful Show-Case, of which the following is a specification.

My invention relates to improvements in show-cases, and more particularly to what 10 may be called "portable" show-cases, by which latter expression I mean small show-cases adapted to be carried at will from place to place or exhibited in shop-windows or on counters, &c.

15 I have illustrated the preferred form of my invention in the accompanying drawings, in which similar letters of reference designate corresponding parts.

Figure 1 is a top view; Fig. 2, a cross-section taken on the lines 2 2 of Fig. 1; Fig. 3, a view, partly in section and partly an outside view, being a cross-section taken on the line 3 3 of Fig. 2 and looking rearward, and Fig. 4, a rear view.

20 Referring to the drawings, A represents a frame or main body portion which may be of any suitable material and any suitable dimensions and shape.

25 B represents a top or cover which will preferably be of glass or other transparent material. As shown, this top is made either partially or wholly removable by being movably arranged in slides or grooves a, arranged in the sides of the frame A. The cover B is 30 also shown as provided with a back piece b, the two being secured together in any suitable manner.

35 Arranged within the frame and intermediate the top and bottom thereof is a false bottom or display-board C, which will preferably be arranged, as shown, at an incline and provided with suitable retaining devices for holding in position the goods to be exhibited. These retaining devices are shown 40 as being grooves or depressions adapted to receive and retain articles of similar shape; but the form and kind of these retaining devices may be varied at will. The display-board may be supported in any suitable 45 manner, although, preferably, it will rest on the inclined supports c'. As shown, the display-board does not continue to the back of the case, but is terminated to leave a space at the rear or top of the show-case for the reception of an advertising-plate D. This plate D 50 will preferably be removable, so that the ad-

vertising thereon can be changed or so that any one of a number of plates may be substituted at will. Preferably the inclined supports c' c' will be continued to the rear of 60 the display-board and act as a support for the removable advertising-plate, thus supporting the board and plate in substantially the same plane.

65 The arrangement of the display-board intermediate the top and bottom of the show-case evidently leaves a space E, which may be used as a receptacle for additional goods, thus making it unnecessary to remove the goods from the display-board. As shown 70 more particularly in Fig. 4, this space is closed by a door F, which may be arranged to open and close in any suitable manner, although, preferably, it will be hinged, as shown, to the lower framework of the show-case. 75 As shown, it is provided with a catch f, which is suitably arranged to swing on a pivot f'. This catch, as shown, consists of a straight bar provided with a recess or slot f². Arranged on the back piece b of the cover is a 80 suitable receiving means forming the other part of the latch, such as a pin f⁴, provided with an enlarged head f³. The slot f² is swung to engage with the pin f⁴ and underneath the enlarged head f³. As a result 85 when the cover is closed and the door is closed and the catch swung into locking position the entire show-case is locked in closed condition. By unfastening the catch it is possible to open either or both the cover and 90 the door, so as to obtain access to either the display-board or the receptacle. The pin f⁴ serves also as a finger-hold to move the cover B.

95 What I claim as new is—

1. In a show-case, the combination of an inclined display-board, an advertising-plate supported in substantially the same plane as the display-board and movable independently of the board, and a removable cover for 100 both the plate and board.

2. In a show-case, the combination of a display-board, an advertising-plate supported in substantially the same plane as the board, a goods-receptacle arranged under the 105 board and plate, and a removable cover for both the plate and board.

3. In a show-case, the combination of a display-board, a removable advertising-plate, and a removable cover for both of the 110 same.

4. In a show-case, the combination of a

display-board, a removable cover for the same, a goods-receptacle, a door therefor, and a catch comprising two parts, one part arranged on the cover, and the other part, on the door, and adapted when interlocked to maintain both the cover and door in a closed position.

In witness whereof I have signed my name to the foregoing specification in the presence of two subscribing witnesses.

OTTO KAMPFE.
